UNITED STATES PATENT OFFICE

2,390,657

COMBINATION CIGARETTE DISPENSER AND
ASH TRAY

Earl R. Loudermilk, Kansas City, Mo.

Application June 28, 1943, Serial No. 492,637

5 Claims. (Cl. 312—97.1)

My invention relates to a combination cigarette dispenser and ash tray and it includes a magazine having a rotatable member provided with a plurality of compartments preferably in the form of radial slots for holding a supply of cigarettes. The magazine also has a stationary bottom with a radial delivery opening through which the cigarettes may be dispensed as desired by turning the rotatable member to successively bring the radial slots into coincidence with the delivery opening.

The device may also be employed for other purposes, such, for example, as a cocktail table, lamp table, a confection dispenser, etc.

Obviously the compartments in the magazine may be made in various shapes and sizes for holding various articles besides cigarettes, and I reserve all rights to such changes in the construction and operation of the device, as properly fall within the scope of the invention as claimed.

In order that the invention may be fully understood, reference will now be had to the accompanying drawings, in which:

Fig. 1 is a perspective view of the device.

Fig. 2 is a side elevation partly in section of the upper portion of the device.

Figs. 3, 4 and 5 are perspective views of different elements constituting the magazine.

Fig. 6 is a fragmentary sectional view of a modified form.

Referring in detail to the different parts, 2 designates a magazine for holding articles to be dispensed thereby. In its preferred form the magazine comprises a rotatable member 4, a removable lid 6 and a stationary bottom plate 8. The foregoing elements are preferably but not necessarily of circular form as shown.

The rotatable member 4 has a plurality of compartments 10 extending downwardly therethrough. Obviously these compartments may be of various shapes and sizes, depending largely on the kind of goods with which they are to be filled. In the present instance I have shown the compartments 10 in the form of slots of uniform size and radially disposed with respect to the vertical axis of the rotatable member 4.

The upper portion of the rotatable member 4 has a recess 12 for reception of the lid 6 so that the upper surface of the latter will be flush with the uppermost surface of the rotatable member, as shown by Figs. 1 and 2. Obviously the lid 6 may be dispensed with since it is not necessary for the operation of the magazine. However, it constitutes a desirable element as it excludes dust from the compartments 10. Consisting prefer-

ably of glass, it also enhances the appearance of the magazine and enables the upper portion of the latter to be utilized as a cocktail table, lamp table, etc.

5 The stationary bottom plate 8 of the magazine has a delivery opening 14 extending downwardly therethrough and of substantially the same length and width as each compartment 10. The delivery opening 14, like the compartments 10, is radially disposed with respect to the axis of the bottom plate 8, so that when an article is desired it is only necessary to turn the member 4 until a filled compartment is brought into coincidence with the delivery opening.

10 The articles from the magazine 2 are preferably delivered upon a shelf 16 preferably of circular form like the magazine. The magazine 2 and the shelf 16 are supported by a standard 18 rising from a base 20 preferably of circular form to conform with the shape of the magazine and the shelf.

15 In order to facilitate assembly of the shelf 16 with the standard 18 the latter is preferably made in two pieces comprising a lower section 22 and an upper section 24. Various means may be employed for detachably connecting the sections 22 and 24, so that the shelf can be readily assembled with the standard. In the present instance I have shown the lower section 22 provided with a centrally-disposed upwardly extending stud 26 which projects through a central hole 28 in the shelf 16 and enters a centrally disposed counterbore 30 in the upper section 24. The stud 26 is secured from accidental displacement by a transverse pin 32 fixed to the upper section 24 and passing through a longitudinal slot 34 which divides the stud 26 into two parts which are firmly clamped against the pin 32 when their conical upper ends 36 enter a cavity of similar form in the upper end of the counterbore 30.

20 The magazine 2 is held upon the upper section 24 of the standard 18 by means of a stud 38 which extends upwardly through central openings 40, 41 and 39 in the bottom plate 8, the rotatable member 4 and the lid 6, respectively. The bottom plate 8 has lugs 42 that enter corresponding recesses 43 in the upper portion of the standard 18 and thereby prevents the bottom plate 8 from rotating with member 4.

25 An ash tray 44 of suitable configuration is removably secured upon the magazine 2 by the stud 38 which enters a counterbore in the ash tray, Fig. 2. Suitable means such as a bayonet joint 46 serves to removably hold the ash tray

and the magazine upon the stud 38. The upper surface of the ash tray 44 has one or more recesses 48 for reception of a like number of cigarette stubs.

The entire device may be made of plastics, wood, metal, or a combination of the foregoing.

In practice the ash tray 44 and the lid 6 are removed to permit filling of the compartments 10 with articles to be dispensed, after which the lid 6 and the ash tray 44 are replaced to hold the several parts in assembly. If the device is to be used solely for dispensing cigarettes, enough compartments 10 are preferably employed for holding the contents of a package, and if desired the compartments may be made deep enough so that each will hold two or more cigarettes. When the compartments are being loaded care should be taken to prevent turning of the rotatable member 4 to carry any of the compartments into coincidence with the delivery opening 14, but after the compartments have been supplied cigarettes may be obtained when desired by turning the rotatable member 4 to successively bring filled compartments into coincidence with the delivery opening 14. To facilitate removal of the lid 6 and turning of the rotatable member 4, the latter has a number of marginal recesses 15 any of which is adapted to receive the tip of a finger.

When a more simple and economical form of the device is desired the shelf 16, standard 18 and the base 20 may be dispensed with as shown by Fig. 6, in which event the stationary bottom plate 8a is provided with legs 50 fixed at their upper ends to the underside of the bottom plate and adapted to rest at their lower ends upon the top of a table or other flat surface G. The bottom plate 8a is provided with a fixed centrally disposed stud 38a which extends upwardly through axial openings 41a and 39a in the rotatable member 4a and the lid 6a, respectively, and may be locked to the ash tray 44a, in the same manner as disclosed by Fig. 2. The bottom plate 8a is provided with a delivery opening 14a, which communicates with a delivery chute 8b, fixed to the underside of the bottom plate, so that when a cigarette H falls from a compartment 10a, registering with the delivery opening 14a, it will be delivered by the chute 8b within convenient reach upon the surface G.

While I have shown and described two forms of the device, I reserve all rights to such other forms and modifications thereof as properly fall within the spirit and scope of the invention as claimed.

Having thus described my invention, what I claim and desire to secure by Letters Patent, is:

1. A dispensing device comprising a magazine having a horizontally disposed rotatable member provided with a recess in its upper surface and a circumferential rim encompassing said recess and projecting slightly above the surface thereof, said rotatable member also having a plurality of radial compartments open at the top and bottom and communicating at their upper portions with the recess, a lid disposed in the recess to cover the compartments and of a thickness equal to the depth of the recess to cooperate with the top of the rim in providing a smooth surface adapted to function as a table top, a stationary bottom plate disposed immediately beneath the rotatable mem-

ber and provided with a delivery opening with which the compartments are adapted to successively communicate when the rotatable member is operated, and supporting means for the magazine provided with a vertical element which extends through axial openings in the lid, the magazine and the stationary bottom plate.

2. A dispensing device comprising a magazine having a horizontally disposed rotatable member provided with a plurality of radial compartments open at the top and bottom, a lid resting on top of said rotatable member to cover the compartments, a stationary bottom plate disposed immediately beneath the rotatable member and provided with a delivery opening with which the compartments are adapted to successively communicate when the rotatable member is operated, and supporting means for the magazine provided with a vertical element upon which the rotatable member is journaled.

3. A dispensing device comprising a magazine having a horizontally disposed rotatable member provided with a plurality of radial compartments open at the top and bottom and adapted to receive articles to be dispensed, a lid resting on top of said rotatable member to cover the compartments, a stationary bottom plate disposed immediately beneath the rotatable member and provided with a delivery opening with which the compartments are adapted to successively communicate when the rotatable member is operated, a shelf disposed below the stationary bottom to receive articles delivered by the magazine, and supporting means for the magazine and the shelf provided with a reduced upper portion upon which the rotatable member is journaled.

4. A dispensing device comprising a magazine having a horizontally disposed rotatable member provided with a plurality of radial compartments open at the top and bottom, a removable lid resting on top of said rotatable member to cover the compartments, a stationary bottom plate disposed immediately beneath the rotatable member and provided with a delivery opening with which the compartments are adapted to communicate when the rotatable member is operated, supporting means for the magazine, and cooperating means on the stationary bottom plate and the supporting means for preventing the former from rotating upon the latter.

5. A dispensing device comprising a magazine having a horizontally disposed rotatable member provided with a plurality of radial compartments open at the top and bottom, a transparent lid resting on top of said rotatable member to cover the compartments, a stationary bottom plate disposed immediately beneath the rotatable member and provided with a delivery opening with which the compartments are adapted to communicate one at a time when the rotatable member is operated, a standard having a reduced upper terminal extending through central openings in the above-mentioned parts of the magazine and upon which the rotatable member is journaled, cooperating means on the stationary bottom plate and supporting means for preventing the former from rotating upon the latter, and a base upon which the standard is mounted.

EARL R. LOUDERMILK.
